UNITED STATES PATENT OFFICE.

ERWIN R. STOEKLE, OF MILWAUKEE, WISCONSIN, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Original application filed March 20, 1916, Serial No. 85,457. Patent No. 1,353,976, dated September 28, 1920. Divided and this application filed August 30, 1920. Serial No. 406,858.

To all whom it may concern:

Be it known that I, ERWIN R. STOEKLE, a citizen of the United States, residing at Milwaukee, in the county of Milwaukee, State of Wisconsin, have invented certain new and useful Improvements in Electron-Discharge Devices, of which the following is a full, clear, concise, and exact description.

This invention relates to electron discharge devices and an object is to construct a device of the above character which will have a much larger power capacity than those heretofore made.

In electron discharge devices of the audion 15 and other types in which two or more elements are used, one of the elements is usually heated and becomes a source of electrons. The other element, called the anode, is usually left cold. Under the action of an electric field, in which the anode is made positive, the electrons from the heated element travel towards the anode and acquire a velocity which, in case of a strong electric field, 20 may be exceedingly high. As a result of the 25 electronic bombardment to which it is thus subjected, the anode becomes heated. In the case of such high vacua as are used in vacuum tubes of this type, it is clear that this 30 heat must be dissipated, almost entirely by radiation.

It has been found that the capacity of these thermionic tubes to handle electric power is limited chiefly by the ability of the anode to dissipate the heat due to bombardment for, when an attempt is made to increase the output of a given tube beyond a certain limit, the anode may be heated to such a degree that an excessive amount of 35 occluded gas is liberated, thus diminishing 40 the vacuum or the anode may actually be heated to its melting point, resulting in the destruction of the tube. In still other cases the anode may become heated to such a degree that the anode acts as a source of electrons and thereby causes trouble in the 45 operation of the tube.

In this invention, then, the purpose is to so construct and arrange the anode element that it will be able to dissipate a much larger amount of heat than heretofore and to do this without having the anode excessively heated. This result has been obtained by making the containing vessel of the vacuum tube of metal and using the metallic vessel

as the cold element or anode. It is apparent 55 that the much larger surface thereby afforded will permit of greater radiation and at the same time further dissipation of heat is made possible by convection.

To assist in this latter, it has been found 60 desirable to cool the tube by means of a fan or by immersing the tube in water, or oil, or other suitable cooling agent.

The subject matter above described is claimed in my application which has matured into Patent 1,353,976, dated September 28, 1920, on vacuum tube devices, of which 65 this is a division.

An object of this invention is to improve upon the electrode supporting arrangement 70 for devices of this character and especially to utilize one of the electrodes as a means of support for another electrode.

This invention will be better understood by reference to the following detailed description taken in connection with the accompanying drawing, in which Fig. 1 represents an embodiment of this invention in which the metallic container is cylindrical in form and Fig. 2 is a cross sectional view 75 80 of the same.

Referring to the drawing, the vacuum tube disclosed therein comprises a metallic tube 1 having flared ends 25 into which fit glass members 3 and 4, tapered ground ends 5 and 6 making close and intimate contact with the flared ends 25 of the metallic tube. In addition to these ground joints, it is, in general, desirable to further improve the seal by 85 means of suitable sealing compounds. 90

Through the center of the tube extends a filament 8 to the ends of which are fastened metallic rods 9 and 10. Rod 10 is, in turn, fastened to two lead-in wires 11 and 12 which pass through the glass member 4 at different points, and are externally connected to a common lead 13. Similarly, the metallic rod 9 is connected to two lead-in wires 14 and 15, which pass through different points of glass member 3 and are externally connected to a common lead 16. The filament leads 13 and 16 are branched as above described for the purpose of reducing the amount of current carried by a single wire sealed through one of the glass members. 95 Leakage, at the point where a lead-in wire is sealed through glass, frequently occurs when large currents pass through the lead-in wires. 100 105

Anode 1 is preferably cylindrical in shape as indicated in the cross sectional view shown in Fig. 2.

In order to allow for the expansion and 5 the contraction of filament 8, due to changes in temperature, it is preferable to support one of the rods 9, for example, by a coiled spring 17, the other end of which is attached to the glass member 3.

10 The grid or control electrode for the tube comprises a helical wire 18 having its turns properly spaced and supported by a plurality of longitudinal rods 19 of conducting material. These rods 19 are fastened at 15 either end to spacing and supporting members 20 and 21 preferably of insulating material such as glass. The size of the blocks or spacing members 20 and 21 is such that the blocks contact at a plurality of points 20 with the metallic container 1, whereby the control electrode 18 is held in place within the metallic container. The size of these spacing members 20 and 21 however should be such as to allow the control electrode with 25 the spacing members to be forced into its proper position in the metallic tube 1 during the manufacture of the device. The grid is provided with a lead in wire 27.

Rods 9 and 10 which are fastened to the 30 opposite ends of the filament 8, pass freely through the apertures 22 and 23 in the spacing members 20 and 21 so as to allow for the free expansion or contraction of the filament.

It is to be understood that the electron 35 discharge device above described may be variously modified without departing in any measure from the spirit of this invention as defined in the appended claims.

What is claimed is:

40 1. An electron discharge device comprising an evacuated vessel having an inwardly projecting neck, a block of insulating material adjacent said neck, an electrode unit supported from said block, and an element of insulating material connected to the end 45 of said unit remote from said neck and slidably contacting with the walls of said evacuated vessel.

50 2. An electron discharge device comprising a cylindrical vessel having an inwardly projecting neck, a block of insulating material adjacent said neck, an electrode unit supported from said block, and a second block of insulating material connected to the 55 end of said unit remote from said neck and slidably contacting with the walls of said evacuated vessel.

60 3. An electron discharge device comprising an evacuated vessel, electrodes in said vessel, lead-in wires for said electrodes passing through one end of said vessel, a block of insulating material adjacent said end for supporting said electrodes, and a second block of insulating material near the end of 65 said electrodes remote from the end of said

vessel through which the lead-in wires pass, said second block being connected to said electrodes and being slidably in contact with the walls of said vessel.

4. An electron discharge device comprising 70 an evacuated vessel containing an electrode unit, lead-in wires sealed in through said vessel at one end thereof, and a block of insulating material at either end of said unit for supporting said unit, said blocks being 75 connected to each other only by a path composed substantially entirely of conducting material.

5. An electron discharge device comprising 80 an anode, a plurality of spaced blocks supported by said anode, a helical electrode, and supporting wires for said helical electrode fastened to said blocks.

6. An electron discharge device comprising 85 an anode, a plurality of spaced blocks of insulating material supported by said anode, a second electrode and supporting wires for said second electrode fastened to said blocks.

7. An electron discharge device comprising 90 an evacuated vessel, a plurality of spaced blocks of insulating material slidably in contact with the walls of said vessel and supported thereby, and a second electrode spaced between said blocks and supported 95 by said blocks.

8. An electron discharge device comprising 100 an evacuated vessel, a block of insulating material therein, and a resilient electrode supporting member passing freely through an aperture in said block.

9. An electron discharge device comprising 105 an evacuated vessel, a block of insulating material therein, an electrode in said vessel, a coiled spring for resiliently supporting said electrode, said spring being located on that side of said block remote from said electrode and being connected to said electrode by a wire passing through an aperture in said block.

110 10. An electron discharge device comprising 115 an evacuated vessel containing a plurality of electrodes, a block of insulating material, one of said electrodes being supported by said block, a coiled spring for resiliently supporting one of said electrodes, said block being located between said spring and the electrode resiliently supported thereby.

11. An electron discharge device comprising 120 an evacuated vessel containing an electrode, a support for said electrode comprising a block of insulating material, a second electrode, a resilient member, a connection between said second electrode and said member for resiliently supporting said electrode, said connection freely passing through an aperture in said block.

12. A vacuum tube comprising an electrode, two spaced blocks of insulating mate- 125

- rial, an aperture in each of said blocks and a rod freely passing through the aperture in each of said blocks for supporting said electrode.
- 5 13. An electron discharge device comprising a cylindrical anode, a cathode, means near one end of said anode for supporting one end of said cathode, means near the other end of said anode for supporting the 10 other end of said cathode, said second means being slidably in contact with the inner wall of said anode.
14. An electron discharge device comprising an evacuated vessel containing an electrode, a plurality of spaced blocks of insulating material for supporting said electrode, and a metallic member centrally spaced with respect to said supported electrode and passing through apertures in said blocks.
- 20 15. An electron discharge device comprising an evacuated vessel, a portion of its containing wall constituting the anode electrode for said device, a second electrode within said anode, a plurality of spaced insulating 25 means for supporting said second electrode, and a metallic member centrally disposed with respect to said electrodes and passing through apertures in said means.
16. An electron discharge device comprising two spaced insulating blocks, an electrode supported therebetween, and supporting means centrally disposed with respect to said blocks and passing through apertures in said blocks.
- 35 17. An electron discharge device comprising a cylindrical anode, spaced blocks of insulating material within said anode, and supporting means centrally disposed with respect to said anode, said means engaging 40 said blocks and being supported thereby.
18. An electron discharge device comprising a tubular anode constituting a portion of the containing wall of said device, a cathode within said anode, a glass closure 45 for one end of said anode, and a lead-in wire through said glass closure, said anode being flared at the end having said glass closure.
- 50 19. An electron discharge device comprising a cylindrical anode constituting a portion of the containing wall of said device, a cathode cooperating with said anode, a glass closure for one end of said anode, one end of said anode having a non-uniform diameter along that part of the anode in contact with said glass closure, and a lead-in wire through said glass closure.
- 55 20. An electron discharge device comprising a tubular anode member constituting a portion of the containing wall of said device, a cathode cooperating with said anode, a tubular glass closure member for one end of said anode, one of said members being flared at its end which is in contact with 60 the other of said members.
21. An electron discharge device comprising a tubular anode constituting a portion of the containing wall of said device, a cathode cooperating with said anode, glass closures one for each end of said anode, and a lead-in wire through one of said closures. 70
22. An electron discharge device comprising a tubular anode constituting a portion of the containing wall of said device, a cathode and a control electrode cooperating with said anode, glass closures for both ends of said tubular anode, a lead-in wire for said cathode through one of said glass closures, and a lead-in wire for said control electrode through the other of said glass closures. 75
23. An electron discharge device comprising a vessel, an anode, a cathode and an electrode, said electrode being intermediate the anode and the cathode, and a block of insulating material supported by the anode and extending across the end of the anode substantially at right angles to the principal axis of said vessel, longitudinal metal members attached to said electrode and supported in said block, said block also serving as a support for the cathode. 80
24. An electron discharge device comprising a tubular anode constituting a portion of the containing wall of said device, a cathode cooperating with said anode, and lead-in wires for said device passing through opposite ends of said tubular anode. 85
25. An electron discharge device comprising a cylindrical anode, an elongated metallic supporting means coinciding in position with the axis of said anode, two spaced blocks of insulating material engaging said means and another electrode supported by 90 said blocks and said supporting means. 100
26. An electron discharge device comprising a cylindrical anode, a cathode, means near one end of said anode for supporting one end of said cathode, means near the other end of said anode for supporting the other end of said cathode, said second means being slidably supported. 110
27. In an electron discharge device, a cylindrical anode, a block of insulating material supported by said anode near each end thereof, an electrode between said blocks, and supporting means for said electrode carried by said insulating blocks. 115
28. In an electron discharge device, a cylindrical anode, a block of insulating material supported by said anode near each end thereof, electrodes between said block, and supporting means for one of said electrodes carried by said blocks. 120
- 125 In witness whereof, I hereunto subscribe my name this 19th day of August A. D., 1920.
